PACKAGING TRAY FOR SHUCKED OYSTERS

David H. Wallace, Annapolis, and William E. Valliant
and Fletcher Phillips Williamson, Cambridge, Md., as
signors to Otto John Munz, Washington, D.C.

Filed June 3, 1959, Ser. No. 56,190

Term of patent 14 years

(Cl. D58—13)

FIG. 1.

FIG. 3.

FIG. 4.

FIG. 5.

FIGURE 1 is a top plan view of a packaging tray for shucked oysters, showing our new design;

FIGURE 2 is a side elevational view thereof;

FIGURE 3 is a cross-sectional view taken on line 3—3 of FIGURE 1;

FIGURE 4 is a cross-sectional view taken on line 4—4 of FIGURE 1 on an enlarged scale; and

FIGURE 5 is an end elevational view thereof.

We claim:

The ornamental design for a packaging tray for shucked oysters, as shown.
